Inc., Brooklyn, N. Y., a corporation of New
York

Application October 5, 1950, Serial No. 188,496

2 Claims. (Cl. 65—13)

1

This invention relates to a combination holder and receptacle such as a cocktail glass and the like article.

An object of this invention is to provide a device of the character described comprising a metal holder and a glass receptacle therein with spring means on the holder to retain the receptacle within the holder.

Yet another object of this invention is to provide a device of the character described comprising a holder, said holder comprising a base, a stem attached to the base, a perforated metal housing attached to the upper end of the stem, a spring clip attached to the bottom of the metal housing, a glass receptacle fitted within the housing and provided with an annular groove receiving spring fingers on the clip for retaining the receptacle within the housing, said receptacle being removable from the housing for washing, cleaning or replacement.

Still another object of this invention is to provide in an article of the character described, a single means for attaching the metal housing to the stem and the spring clip to the bottom of the housing.

A still further object of this invention is to provide a strong, rugged and durable device of the character described, which shall be relatively inexpensive to manufacture, easy to assemble and disassemble, which shall be easy to keep clean, and which shall yet be practical and efficient to a high degree in use.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims.

In the accompanying drawings in which is shown various illustrative embodiments of this invention,

Fig. 1 is a front perspective view of an article embodying the invention;

Fig. 2 is a vertical axial cross-sectional view through said article; and

Fig. 3 is a cross-sectional view taken on line 3—3 of Fig. 2 with the glass receptacle removed.

Referring now in detail to the drawing, 10 designates a combination article embodying the invention. The same comprises a holder 11 and a receptacle 12 carried thereby. The holder 11 comprises a base 13 which may be made of sheet metal. The base 13 is annular and may be hol-

low at its underside. It is provided with an annular inwardly rolled bottom outer rim 14 from which extends upwardly, an annular portion 15 of wavy transverse cross-section, merging with a top flat annular portion 16. Said flat portion 16 has a central hole 17.

Mounted on the top portion 16 is a rod-like stem 18 which may be of any ornamental shape. The stem 18 has a bottom surface 20 contacting the upper surface of portion 16. It is formed at its underside with an upwardly extending blind screw threaded opening 21 registering with the opening 17 in said portion 16. The stem 18 has a top flat circular surface 22 likewise formed with a central blind downwardly extending screw threaded opening 23.

Means is provided for attaching the base to the stem. Said means comprise a screw 24 passing through the opening 17 and screwed within the threaded opening 21. A washer 26 may be interposed between the head of the screw and said portion 16 of the base.

Mounted on the upper end of the stem 18 is a housing 27. The housing 27 may be made of metal. It comprises a flat bottom portion 29 resting on the flat surface 22 at the upper end of the stem 18. The flat portion 29 is formed with a central through opening 30 registering with the screw threaded opening 23 in the stem. Extending upwardly from the flat portion 29 is an annular curved portion 31 which may be perforated or formed with ornamental openings 32. Said portion 31 may be formed at its upper end with curved or decorative edges 33.

Mounted within the housing 27 is a spring clip 35. Said spring clip 35 may be made of a single piece of spring steel. It comprises an annular flat central bottom portion 36 formed with a central opening 37 registering with the openings 30 and 23. Extending upwardly from the flat portion 36 are a plurality of equi-angularly spaced spring fingers 38. Three such fingers are shown for the purpose of illustration, it being understood that any suitable number of such fingers may be provided.

At the upper end of each spring finger 38 is an inwardly extending curved or hooked tongue 39. The fingers 38 are similar. It will be noted that said fingers are disposed just inside the inner surface of the wall 31. The tongues 39 are disposed below the level of the perforations 32 so that they can not be seen through said perforations.

A single means is provided for attaching the spring clip 35 and the housing 27 to the upper

end of the stem 19. For this purpose the rim at the opening 37 is formed with a downwardly and inwardly extending annular flange 42. Passing through the opening 37 and through the opening 30 in the bottom wall 29 of the housing 27, is the shank of a screw 43. The shank of the screw is screwed into the threaded opening 23. The head of the screw engages the flange 42.

Interposed between said portion 36 of the spring clip and portion 29 of housing 27 is a lock washer 45. The head of the screw presses against the flange 42 and serves to clamp the housing to the stem and the spring clip to the housing.

Disposed within the housing 27 is the glass receptacle 12. Said receptacle has an outer shape conforming substantially to the shape of portion 31 of the housing 27. The upper edge 46 of the glass receptacle is disposed above the upper edge 33 of housing 27. The receptacle 12 is thickest at its bottom and becomes thinner toward the top. It is formed in its outer surface with an annular groove 50 into which the curved spring tongues 39 may snap for retaining the glass receptacle in contact with the inner surface of upper portion of wall 31.

It will be noted that the receptacle contacts the inner surface of wall 31 and fits snugly therein.

If it is desired to clean the glass receptacle 12, said receptacle may be pulled out of the holder, nevertheless, the spring clip will keep the glass receptacle from accidentally falling out. It will be observed that the holder 11 may be disassembled or assembled easily.

While the article 10 is shown herein in the form of a cocktail glass, it will be understood that other similar articles may embody the present invention.

It will now be understood that the glass receptacle 12 contacts the housing 27 only at its inner surface and adjacent the upper end thereof as shown in Figure 2 of the drawing. Below said point of contact, the receptacle is spaced from the housing. Furthermore, the glass receptacle does not contact the central bottom portion 36 of the spring clip but only engages free flexing portions of the spring fingers 38. The spring fingers 38 do not contact the holder. They are spaced from the holder and hence serve to resiliently press the receptacle into contact with the inner surface of the housing 27 adjacent the upper end of the latter. It is well known that glass receptacles will vary in size due to unequal contraction upon cooling after being molded. With the present construction, the glass receptacle is always pressed against the housing even if the size varies in the cooling process.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth, or shown in the accompanying drawings, is to be interpreted as illustrative and not in a limiting sense.

Having thus described my invention I claim as new and desire to secure by Letters Patent:

1. An article of the character described comprising a base, a stem on the base, said stem being formed at its upper end with a central

screw threaded opening, a housing having a flat bottom wall contacting the upper end of the base and formed with a central opening, said housing having an upwardly and outwardly curved annular wall extending from said flat wall, a receptacle within said housing formed with an external annular groove, a spring clip within said housing having a bottom annular portion disposed between said receptacle and said flat wall and formed with a central opening, said spring clip having fingers provided with portions engaging within said annular groove, and a screw having a head contacting the central opening of said bottom portion of said spring clip at said opening and being provided with a shank passing through the opening in the flat wall of the housing and screwed within the threaded opening at the upper end of the stem, said fingers being spaced from said housing and holding said receptacle snugly into said housing, said receptacle touching said housing only adjacent the upper end of the latter and being spaced from the bottom of the spring clip.

2. An article of the character described comprising a base, a stem on the base, said stem being formed on its upper end with a central screw threaded opening, a detachable housing having a flat bottom wall contacting the upper end of the base and formed with a central opening, said housing having an upwardly and outwardly curved annular wall extending from said flat wall, a receptacle within said housing formed with an external annular groove, a spring clip within said housing having a bottom annular portion disposed between said receptacle and said flat wall and formed with a central opening, said spring clip having spring fingers provided with portions engaging said annular groove, and a screw having a head contacting the central opening of the bottom of said spring clip and being provided with a shank passing through the opening in the flat wall of the housing and screwed within the threaded opening in the upward end of the stem, said receptacle being thickest at the bottom and becoming thinner toward its upper edge, said receptacle contacting said holder only adjacent the upper end of the latter and being otherwise spaced from the holder, said spring clip serving to resiliently hold the receptacle against the inner surface of the holder adjacent the upper end thereof.
